UNITED STATES PATENT OFFICE.

JESSE A. B. SMITH, OF STAMFORD, CONNECTICUT, ASSIGNOR TO UNDERWOOD TYPEWRITER COMPANY, OF NEW YORK, N. Y., A CORPORATION OF DELAWARE.

TYPEWRITING MACHINE.

Application filed December 11, 1920, Serial No. 429,840.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to typewriting ma-

10 chines of the continuous billing variety, one form of which is described in the patent to Wernery & Smith, No. 1,132,055, in which the typewriter carriage comprises an extension upon which is reciprocable a carbon-paper carriage adapted to carry carbon-sheets for the reproduction in carbon copies of matter typed upon an outer sheet.

In machines of the Wernery & Smith type, the carbon-sheets are usually of limited 20 length which are clipped to clip-bars upon the carbon-paper carriage. When any sheet is worn out the clip is released and a new sheet clipped in place of the exhausted one, which is removed.

25 The present invention provides a continuous carbon-paper supply. The carbon papers are cross-folded in the form of webs and stored in containers or magazines located between the continuous work-sheets.

30 Means are provided whereby a fixed portion of the carbon-paper web is clamped in position, and no new portion of the web is taken from the magazine unless desired. At such times the clamps are released and a new portion of carbon-paper, drawn off 35 whereupon the clamps are restored.

Other features and advantages will hereinafter appear.

In the accompanying drawings,

40 Figure 1 is a perspective view of a carbon-paper magazine.

Figure 2 is a side view, largely sectioned, of an Underwood continuous billing machine with the new carbon-paper supply 45 mechanism mounted on a carbon-paper carriage, and showing the carbon-papers clamped against withdrawal from their magazines.

Figure 3 is a view of a portion of the apparatus in Figure 2, showing the clamps in ineffective position to allow withdrawal of the carbon-paper from the magazines.

Figure 4 is an end view of the carbon-

paper carriage with the magazines removed.

Figure 5 is a plan view of the device 55 shown in Figure 2.

In the usual Underwood continuous billing machine, continuous work-webs 1, 2, 3 and 4 are led down over a rear paper-table 5, forming part of the typewriter carriage 6, 60 and are held against the platen 7 by the usual rear and front feed-rolls 8 and 9.

The webs are interleaved with carbon-sheets 11, 12 and 13, which normally extend as far as the printing line, and, from that line, the webs and carbon-sheets, in the operation of typing, pass above the usual front knife 15 and lie upon a front paper-table 16. When a form on webs 1, 2, 3 and 4 is fully typed, the platen is swung up in its swing frame 17 by rotating the frame about the front shaft 18 by means of a gage member 21. The frame is normally held in position, shown in Figure 2, by a spring catch 19^a 70 engaging a pin 17^a on the frame, from which it may be released by handle 19. The platen is swung upwardly a distance such that the various sheets around the platen may be drawn out to form substantially a continuous straight line with the sheets as fed from the rear (see patent to Wernery & Smith, noted above). The straightening of the sheets makes it possible to retract the carbon-sheets without undue friction being created by the webs, which would be the case if the webs followed a curved path. The various sheets are gaged against a gage 20 adjustably mounted on the usual gage member 21. The webs are held in the gaged position while the carbon-sheets are pulled 80 backwardly by pushing upon the usual handle 22 to carry rearwardly the carbon-paper carriage 23. The carriage travels on side rails 24 connected at the rear by a cross-bar 25 to form a rear extension of the typewriter carriage 6. Usually there is provided a stop 26, which serves to arrest the carbon-paper carriage when the latter is pushed rearwardly by the handle 22.

According to the present invention, the 100 carbon-sheets, instead of being short sheets, as is customarily the case, are in the form of webs 30 of considerable length, these webs supplying the carbon-sheets 11, 12 and 13. The webs 30 are housed within boxes 105 or magazines 31 of any suitable construction,

and here shown as in the form of flat boxes provided with slidable covers 32. The boxes rest flatwise one above the other, in vertical alignment, and in order to provide a space 5 between the top of one box and the bottom of the box above to allow the continuous work-webs to pass through, the side members 33 of each box, at the ends of the box, project slightly below the bottom of the box 10 as at 34.

The boxes 31 are positioned on the movable carbon-paper carriage between side walls 40 fixed to a base 41 provided with rollers 42 operating on the side rails 24. 15 The rear ends of the side members 40 are bent slightly inwardly forming a rear limiting means 44 for the boxes, which are positioned between the side members. The boxes are of a width substantially equal to 20 the distance between the side members, thus avoiding lateral movement of the boxes. To prevent forward movement of the boxes there are provided cross-bars 45, extending, at the front of the boxes, between the side 25 walls 40. The boxes are therefore confined between the side walls, the bent ends 44 at the rear edges of the side walls, and the front cross-bars 45. The side walls are cut out, as shown in Figures 2 and 3, to allow 30 access to the boxes, when it is desired to remove them from the carriage.

A forward extension 50 is formed integral with each side member 40, and has fixed to the inner surface thereof lower jaws 51 of 35 a carbon-paper clamping device. Said jaws 51 are provided with flanges 52 adjacent the extensions 50. Adapted to fit between the side members and enclose said lower jaws is a vertically reciprocable slidable 40 frame composed of side members 60 and upper jaws 65. The width of said frame member is substantially equal to the distance between the inner surfaces of the side members 40 so that there is very little lateral play. The side members 60 are formed 45 with openings 62 just large enough to permit the lower jaws 51 to pass therein. Openings 62 lead to larger cut-out portions 63 of substantially the same width as the jaws 50 51, so that once said jaws are housed within said cut-out portions, members 60 are constrained to move in a vertical direction. Adjacent the upper ends of the cut-out portions are fixed to the side members 60, upper 55 jaws 65 having flanges fixed to the members 60 at 61 and co-operating with the lower jaws 51. The fixed jaws 51 form a lower set of jaws and the movable jaws 65 form an upper set of jaws, of which each lower jaw 60 61 and its co-operating upper jaw 65 form a pair of relatively movable clamping jaws. A spring 70, connected to a pin 71 on the side member 40 and to the upper part of side member 60, is provided at each side 65 to keep member 60 in lowered position, so

that upper jaws 65 will be pressed normally against lower jaws 51. The carbon-webs pass through openings 35 in the upper portion of the boxes, and between the upper and lower jaws to the platen. When the jaws 70 are in closed position, the carbon-papers are gripped and clamped in position, and unwinding of the carbon-webs is prevented.

When the portions of the carbon-papers being used are exhausted, and it is desired to withdraw fresh portions from the carbon-webs, means are provided for separating the upper and lower jaws of the clamps to permit such withdrawal. Said means comprises cams 80 mounted beneath 75 side members 60 and fixed to a shaft 81 journaled in the extensions 50 of side members 40. The shaft is provided at one end outside the side member 40 with a handle 82. When the handle is in the Figure 2 80 position, the upper jaws are in lowered position, and the clamp is effective to prevent withdrawal of fresh carbon-paper. When the handle is rotated rearwardly to the Figure 3 position, the side members 60 are 85 raised by the cams 80 and the upper jaws are separated from the lower jaws to permit unwinding of carbon-paper from the carbon webs. A two-way spring fixed to a pin 85 on extension 50 and a second pin 86 on 90 handle 82 will hold the handle in the Figure 2 or Figure 3 position, according as the spring lies to one side or the other of the axis of shaft 81.

In the operation of the device, therefore, 100 assume the parts of the machine and the various sheets to be in the position shown in Figure 2. As the forms on webs 1, 2, 3 and 4 are typed, the webs and their carbon-sheets will be advanced around the platen, 105 drawing the carbon-paper carriage forwardly along rails 24. When the forms have been fully typed, the platen is swung upwardly carrying the gage 20 forwardly. The forms and carbon-sheets are then drawn 110 forwardly and gaged against the gage 20. Only the webs are held together while the handle 22 is pushed rearwardly, and the carbon-paper carriage moves back drawing the carbon-sheets with it. When the used 115 portions of the carbon-sheets become worn and it is desired to substitute new portions, the webs and carbon-sheets are again gaged by the gage 20, but instead of holding only the webs, the webs and carbon-sheets are held. Handle 82 is then swung rearwardly to the 120 Figure 3 position raising members 60 and hence upper jaws 65 of the clamps, thus releasing the carbon-sheets. Handle 22 is again pushed rearwardly, but since the carbon-sheets are held at gage 20, the carbon-webs in the boxes 31 will be drawn off. When the carbon-paper carriage reaches its rearmost point, handle 82 is swung forwardly to the 125 Figure 2 position to clamp the carbon-sheets 130

in the new position, and the typed forms and the worn carbon-sheet portions are then torn off together against the knife 15.

Variations may be resorted to within the scope of the invention, and portions of the improvements may be used without others.

Having thus described my invention, I claim:

1. In a typewriting machine, the combination with a carriage, and a platen journaled in said carriage and around which work-webs are adapted to be fed, of an extension of said carriage, a carbon-paper carriage reciprocable upon said extension toward and from the platen, carbon-web-supplying magazines carried by said carbon-paper carriage between the work-webs for containing reserve carbon-paper web supplies interleaved between said work-webs and feedable directly forward into position for active use when required, a space being provided between adjacent magazines for the passage of a work-web, and means to prevent withdrawal of the carbon-paper webs from said magazines, except when a stretch of used carbon is to be replaced by fresh carbon from the reserve. 90
2. In a typewriting machine, the combination with a carriage and a platen journaled in said carriage, of a rear carriage extension, a carbon-paper carriage reciprocable upon said extension toward and from the platen, whereby active stretches of carbon-paper, carried by said carbon-paper carriage and interleaved with work webs, may be repeatedly advanced around the platen and withdrawn until worn out by use, work-web-guiding means for guiding the work-webs across said carbon-paper carriage to the platen, and carbon-paper-reserve holders mounted on said carbon-paper carriage in superposed, but separated, positions to lie between said work-webs, and each arranged to carry between the work-webs a reserve supply of carbon-paper from which fresh stretches of carbon may be drawn straight forward to replace active stretches which have been worn out by use. 100
3. In a typewriting machine, the combination with a carriage, and a platen journaled in said carriage and around which work-webs are adapted to be fed, of an extension of said carriage, a carbon-paper carriage adapted to be reciprocated upon said extension, carbon-web magazines carried by said carbon-paper carriage for containing carbon-paper webs to be interleaved between said work-webs, a space being provided between the magazines for the passage of a work-web, means carried by said carbon-paper carriage for engaging and clamping said carbon-paper webs to prevent withdrawal of fresh portions thereof from said magazines means for releasing said clamping means to permit withdrawal of said 115
- carbon-paper webs, and means for retaining said clamping means in effective or ineffective position. 120
4. In a typewriting machine, the combination with a carriage, and a platen journaled in said carriage and around which work-sheets are adapted to be fed, of an extension of said carriage, a carbon-paper carriage adapted to be reciprocated upon said extension, carbon-paper webs carried by said carbon-paper carriage and adapted to be interleaved between said work-sheets, means for clamping said carbon-paper webs to prevent withdrawal of said webs from said carriage, said clamping means comprising a vertically reciprocable member and co-operating sets of upper and lower jaws, one set of jaws being fixed to said carbon-paper carriage, the other set of jaws being fixed to said vertically reciprocable member, and means for operating said reciprocable member to clamp the carbon-paper webs between said sets of jaws, or release said webs therefrom to allow withdrawal of said webs from said carbon-paper carriage. 130
5. In a typewriting machine, the combination with a carriage, and a platen journaled in said carriage and around which work-sheets are adapted to be fed, of an extension of said carriage, a carbon-paper carriage adapted to be reciprocated upon said extension, carbon-paper webs carried by said carbon-paper carriage and adapted to be interleaved between said work-sheets, means for clamping said carbon-paper webs to prevent withdrawal of said webs from said carriage, said clamping means comprising a vertically reciprocable member and co-operating sets of upper and lower jaws, one set of jaws being fixed to said carbon-paper carriage, the other set of jaws being fixed to said vertically reciprocable member, a shaft journaled in said carbon-paper carriage, a cam member fixed to said shaft for operating said reciprocable member to clamp the carbon-paper webs between said sets of jaws, or release said webs therefrom to allow withdrawal of said webs from said carbon-paper carriage, and a handle fixed to said shaft for operating said cam member. 115
6. In a typewriting machine, the combination with a carriage, and a platen journaled in said carriage and around which work-sheets are adapted to be fed, of an extension of said carriage, a carbon-paper carriage adapted to be reciprocated upon said extension, carbon-paper webs carried by said carbon-paper carriage and adapted to be interleaved between said work-sheets, means for clamping said carbon-paper webs to prevent withdrawal of said webs from said carriage, said clamping means comprising a vertically reciprocable member and co-operating sets of upper and lower jaws, one set of jaws being fixed to said carbon-paper carriage. 125

riage, the other set of jaws being fixed to said vertically reciprocable member, a shaft journaled in said carbon-paper carriage, a cam member fixed to said shaft for operating said reciprocable member to clamp the carbon-paper webs between said sets of jaws, or release said webs therefrom to allow withdrawal of said webs from said carbon-paper carriage, a handle fixed to said shaft for operating said cam member, and a two-way spring fixed to said carbon-paper carriage and said handle to hold said handle, cam member, and reciprocable member in positions corresponding to the effective and ineffective positions of the clamping means.

7. In a typewriting machine, the combination with a carriage, and a platen journaled in said carriage and around which work-sheets are adapted to be fed, of an extension of said carriage, a carbon-paper carriage having vertical side walls and adapted to be reciprocated upon said extension, carbon-paper webs carried by said carbon-paper carriage and adapted to be interleaved between said work-sheets, means carried by said carbon-paper carriage for clamping said webs to prevent withdrawal of fresh portions thereof from said carriage, said clamping means comprising vertically reciprocating members adjacent said vertical walls and co-operating sets of upper and lower jaws, one set of jaws being fixed to a vertical wall of said carbon-paper carriage, the other set of jaws being fixed to an adjacent vertically reciprocable member, said member having cut-out portions into which the jaws on said vertical wall are adapted to pass to guide said member in its vertical movement, and means for operating said reciprocable member to clamp the carbon-paper webs between said jaws, or release said webs therefrom to allow withdrawal of said webs from said carbon-paper carriage.

8. In a typewriting machine, the combination with a carriage, and a platen journaled in said carriage and around which work-sheets are adapted to be fed, of an extension of said carriage, a carbon-paper carriage having vertical side walls and adapted to be reciprocated upon said extension, carbon-paper webs carried by said carbon-paper carriage and adapted to be interleaved between said work-sheets, means carried by said carbon-paper carriage for clamping said webs to prevent withdrawal of fresh portions thereof from said carriage, said clamping means comprising connected vertically reciprocable members adjacent said vertical walls and co-operating sets of upper and lower jaws, one set of jaws being fixed to each of the walls of said carbon-paper carriage, the other set of jaws being fixed to each of said vertically reciprocable members, said members having cut-out portions into which the jaws on said vertical

walls are adapted to pass to guide said frame in its vertical movement, and means for operating said reciprocable members to clamp the carbon-paper webs between said jaws, or release said webs therefrom to allow withdrawal of said webs from said carbon-paper carriage.

9. In a typewriting machine, the combination with a carriage, and a platen journaled in said carriage and around which work-sheets are adapted to be fed, of an extension of said carriage, a carbon-paper carriage having vertical side walls and adapted to be reciprocated upon said extension, carbon-paper webs carried by said carbon-paper carriage and adapted to be interleaved between said work-sheets, means carried by said carbon-paper carriage for clamping said webs to prevent withdrawal of fresh portions thereof from said carriage, said clamping means comprising vertically reciprocable members adjacent said vertical walls, and co-operating sets of upper and lower jaws, one set of jaws being fixed to the walls of said carbon-paper carriage, the other set of jaws being fixed to the vertically reciprocable members, said members having cut-out portions into which the jaws of said first set are adapted to pass to guide said members in their vertical movement, and a cam member for operating said reciprocable members to clamp the carbon-paper webs between said jaws, or release said webs therefrom to allow withdrawal of said webs from said carbon-paper carriage.

10. In a typewriting machine, the combination with a carriage, and a platen journaled in said carriage and around which work-sheets are adapted to be fed, of an extension of said carriage, a carbon-paper carriage having vertical side walls and adapted to be reciprocated upon said extension, carbon-paper webs carried by said carbon-paper carriage and adapted to be interleaved between said work-sheets, means carried by said carbon-paper carriage for clamping said webs to prevent withdrawal of fresh portions thereof from said carriage, said clamping means comprising vertically reciprocable members adjacent said vertical walls, and co-operating sets of upper and lower jaws, one set of jaws being fixed to the walls of said carbon-paper carriage, the other set of jaws being fixed to the vertically reciprocable members, said members having cut-out portions into which the jaws of said first set are adapted to pass to guide said members in their vertical movement, a shaft journaled in said carbon-paper carriage, a cam member fixed to said shaft for operating said reciprocable members to clamp the carbon-paper webs between said jaws, or release said webs therefrom to allow withdrawal of said webs from said carbon-paper carriage, and a handle

fixed to said shaft for operating said cam member.

11. In a typewriting machine, the combination with a carriage, and a platen journaled in said carriage and around which work-sheets are adapted to be fed, of an extension of said carriage, a carbon-paper carriage having vertical side walls and adapted to be reciprocated upon said extension, carbon-paper webs carried by said carbon-paper carriage and adapted to be interleaved between said work-sheets, means carried by said carbon-paper carriage for clamping said webs to prevent withdrawal of fresh portions thereof from said carriage, said clamping means comprising vertically reciprocable members adjacent said vertical walls, and co-operating sets of upper and lower jaws, one set of jaws being fixed to the walls of said carbon-paper carriage, the other set of jaws being fixed to the vertically reciprocable members, said members having cut-out portions into which the jaws of said first set are adapted to pass to guide said members in their vertical movement, a shaft journaled in said carbon-paper carriage, a cam member fixed to said shaft for operating said reciprocable members to clamp the carbon-paper webs between said jaws, or release said webs therefrom to allow withdrawal of said webs from said carbon-paper carriage, a handle fixed to said shaft for operating said cam member, and a two-way spring fixed to said carbon-paper carriage and said handle, to hold said handle, cam member, and reciprocable members in positions corresponding to the effective and ineffective positions of the clamping means.
12. In a typewriting machine, the combination with a carriage, and a platen journaled in said carriage and around which work-webs are adapted to be fed, of an extension of said carriage, a carbon-paper carriage adapted to be reciprocated upon said extension, carbon-web magazines mounted in vertical alignment on said carbon-paper carriage, and carbon-paper webs in said magazines and adapted to be interleaved between said work-webs, said magazines having cut-out portions through which said carbon-webs pass to the platen, said work-webs being adapted to pass between adjacent magazines.
13. In a typewriting machine, the combination with a carriage, and a platen journaled in said carriage and around which work-webs are adapted to be fed, of an extension of said carriage, a carbon-paper carriage adapted to be reciprocated upon said extension, carbon-web magazines mounted in vertical alignment on said carbon-paper carriage, means on said carbon-paper carriage for confining said magazines against all but vertical movement with respect to said carriage, carbon-paper webs in said magazines and adapted to be interleaved between said work-webs, said magazines having cut-out portions through which said carbon-webs pass to the platen, said work-webs being adapted to pass between adjacent magazines, and clamping means on said vertical walls for clamping the carbon sheets in position outside said magazines.
14. In a typewriting machine, the combination with a carriage, and a platen journaled in said carriage and around which work-webs are adapted to be fed, of an extension of said carriage, a carbon-paper carriage having vertical side walls and adapted to be reciprocated upon said extension, carbon-web magazines mounted in vertical alignment on said carbon-paper carriage and spaced vertically one from the other, and carbon-paper webs in said magazines and adapted to be interleaved between said work-webs, said magazines having cut-out portions through which said carbon-webs pass to the platen, said work-webs being adapted to pass between adjacent magazines in the spaces between said magazines, said vertical side walls having cut-out portions to permit access to said magazines.
15. In a typewriting machine, the combination with a carriage, and a platen journaled in said carriage and around which work-webs are adapted to be fed, of an extension of said carriage, a carbon-paper carriage adapted to be reciprocated upon said extension, carbon-web magazines mounted in vertical alignment on said carbon-paper carriage, carbon-paper webs in said magazines and adapted to be interleaved between said work-webs, said magazines having cut-out portions through which said carbon-webs pass to the platen, said work-webs being adapted to pass between adjacent magazines, and clamping means on said carbon-paper carriage for clamping the carbon-webs in position outside said magazines.
16. In a typewriting machine, the combination with a carriage, and a platen journaled in said carriage and around which work-webs are adapted to be fed, of an extension of said carriage, a carbon-paper carriage having vertical side walls and adapted to be reciprocated upon said extension, carbon-web magazines mounted in vertical alignment on said carbon-paper carriage, means on said carbon-paper carriage for confining said magazines against all but vertical movement with respect to said carriage, carbon-paper webs in said magazines and adapted to be interleaved between said work-webs, said magazines having cut-out portions through which said carbon-webs pass to the platen, said work-webs being adapted to pass between adjacent magazines, and clamping means on said vertical walls for clamping the carbon sheets in position outside said magazines.
17. In a typewriting machine, the combination with a carriage, and a platen journaled in said carriage and around which work-webs are adapted to be fed, of an extension of said carriage, a carbon-paper carriage having vertical side walls and adapted to be reciprocated upon said extension, carbon-web magazines mounted in vertical alignment on said carbon-paper carriage, and carbon-paper webs in said magazines and adapted to be interleaved between said work-webs, said magazines having cut-out portions through which said carbon-webs pass to the platen, said work-webs being adapted to pass between adjacent magazines.

nation with a carriage, and a platen journaled in said carriage and around which work-webs are adapted to be fed, of an extension of said carriage, a carbon-paper carriage having vertical side walls and adapted to be reciprocated upon said extension, carbon-web magazines mounted in vertical alignment on said carbon-paper carriage and spaced vertically one from the other, 5 carbon-paper webs in said magazines and adapted to be interleaved between said work-webs, said magazines having cut-out portions through which said carbon-webs pass to the platen, said work-webs being 10 adapted to pass between adjacent magazines, said vertical side walls having cut-out portions to permit access to said magazines, and clamping means on said vertical walls for clamping the carbon-webs in position outside 15 said magazines, said clamping means being releasable to permit withdrawal of said carbon-paper webs from their magazines.

18. In a typewriting machine, the combination with a traveling carriage and a revolute platen journaled therein, of a rear extension of said carriage, a carbon-paper carriage to be reciprocated to and from the platen upon said extension and over 20 which work-webs may pass to the introductory side of the platen, a plurality of carbon-paper magazines mounted upon the carbon-paper carriage to contain supplies of carbon-paper webs to be interleaved between 25 said work-webs, web-gripping means on the carbon-paper carriage for individually gripping said carbon-paper webs, and manually-operable means for operating all of the web-gripping means at a single operation to grip and hold the carbon-paper webs to prevent fresh portions thereof being drawn from said magazines or at a single operation to release said carbon-paper webs to enable fresh portions thereof to be 30 drawn from said magazines.

19. In a typewriting machine, the combination with a traveling carriage and a revolute platen journaled therein, of a rear extension of said carriage, a carbon-paper carriage to be reciprocated to and from the platen upon said extension and over which work-webs may pass to the introductory side of the platen, a plurality of carbon-paper magazines mounted upon the carbon-paper carriage to contain supplies of carbon-paper webs to be interleaved between said work-webs, and web-clamping means on the carbon-paper carriage for clamping the carbon-paper webs to prevent fresh portions thereof being drawn from said magazines; said web-clamping means comprising pairs of relatively movable co-operating clamping jaws, spring-pressed means for

holding said clamping jaws in position to clamp the carbon-paper webs between the 65 jaws of said pairs, and manually-operable means for separating the jaws to release the carbon-paper webs to enable fresh portions thereof to be drawn from said magazines.

20. In a typewriting machine, the combination with a carriage and a platen journaled in said carriage, of work-web-guiding means at the rear of the platen for guiding continuous work-webs to the platen, carbon-webs between the work-webs each 70 including an active portion and a reserve portion, and carbon-web-holding means located between said work-webs and operable to cause the ends of carbon-webs carried by them to be repeatedly advanced around the 75 platen and retracted until worn out by use, and also arranged to feed fresh portions of the carbon-webs carried by them straight forward from the reserve into position for use to replace said ends when the latter 80 have been worn out.

21. A manifolding attachment for typewriters comprising a carrying member; means for mounting said member on the platen carriage of the machine, adapting it 90 for movement towards and away from the line of type-impact; a chambered member mounted upon said carrying member; and a manifolding sheet within said chambered member and adapted to be drawn therefrom 95 to present successive sections in the line of type-impact.

22. A manifolding attachment for typewriters comprising an apertured casing; means for mounting said casing on the 100 platen carriage of the machine; and a manifolding sheet fan-folded within said casing and adapted to be drawn therefrom to present successive sections in the line of type-impact.

23. A manifolding attachment for typewriters comprising an apertured casing; means for mounting said casing on the platen carriage of the machine, adapting it for 110 movement towards and away from the line of type-impact; and a manifolding sheet fan-folded within said casing and adapted to be drawn therefrom to present successive sections in the line of type-impact.

24. In a continuous billing machine, a platen, a traveling carbon-carriage, and a compactly-arranged group of carbon-carrying magazines on the carbon-carriage, for causing the ends of carbon-webs carried by them to be fed around the platen repeatedly 115 until worn, and for then replacing said ends with fresh stretches of carbon.
